UNITED STATES PATENT OFFICE.

CHARLES E. REORDAN, OF DALLAS, TEXAS.

METHOD AND APPARATUS FOR GENERATING MOTIVE FLUID.

1,224,789.

Specification of Letters Patent.

Patented May 1, 1917.

Application filed January 7, 1914. Serial No. 310,856.

To all whom it may concern:

Be it known that I, CHARLES E. REORDAN, a citizen of the United States, residing at Dallas, in the county of Dallas and State 5 of Texas, have invented certain new and useful Improvements in Methods and Apparatus for Generating Motive Fluid, of which the following is a specification.

My invention relates to improvements in 10 methods and apparatus for generating motive fluid and one of the objects of my invention is to provide a source of combustion or combustion chamber, which is disposed outside of the generator and which is arranged 15 to deliver the products of combustion to the generator, and preferably below the water level therein, to generate steam, and a motive fluid, composed of the steam and gases of combustion, for delivery to any 20 of the several forms of steam engines.

It is one of the objects of my invention to effect combustion outside of the generator so that the heat will not be drawn off thereby and for the further reason that I can obtain 25 combustion under a resultantly higher temperature so that the delivered combustion gases to the contents of the generator will have a steam generating efficiency. A further object in effecting combustion outside 30 of a generator is to provide means for more readily controlling the intensity of heat under which combustion is effected, and to provide an external pressure of the desired extent to counteract internal combustion 35 pressure and thereby avoid the necessity of complication in the construction of the combustion chamber to take care of internal pressure.

Other objects and features of my invention 40 will be more fully described in connection with the accompanying drawing and will be more particularly pointed out in and by the appended claims.

The accompanying drawing illustrates the 45 device of my invention in vertical section and illustrates the manner of delivery of the products of combustion to a generator.

As illustrated, 1 designates a generator in the form of a steam boiler in which the 50 water level is indicated at 2.

A combustion chamber is shown at 3 and may comprise a substantially globular casting having an air and oil inlet opening 4, and an outlet opening 5 for the products of 55 combustion, and an inlet opening 6 for an ignition device. The ignition device may

comprise an ignition ball or sphere 7, of hollow construction and having a stem 8 provided with a flange 9 adapted for anchorage to a complementally formed flange on the 60 casing 3. A Bunsen burner or like initial heater is indicated at 10 and extends into the hollow stem 8 for delivery to the ball or sphere 7. The ball 7 will be constructed of a metal which is susceptible of being heated 65 to a very high temperature in a relatively short space of time. The casing 3 is provided with a flange 11 which may be bolted to an extension 12, of the boiler 1, to cause the opening 5 to register with a delivery 70 pipe 13 adapted to extend downwardly into the boiler 1. The combustion delivery pipe 13 is substantially L-shaped and on its upwardly extending terminal 14 I provide a non-return valve which may consist of a casing 15, having a valve seat 16, and adapted to be secured to the terminal end 14 by bolts 17. A check valve 18 is arranged to close 75 passage downwardly through said casing 15 under boiler pressure but to permit passage 80 through said casing 15 to said boiler. Any suitable stop such as indicated at 19 may be provided to limit unseating movement of the valve closure 18. The casing 15 is provided with a discharge opening 20.

A source of supply of combustion supporting media, which may be air, will be supplied to the combustion chamber through the opening 4 by means of a pipe 21. The pipe 21 may be connected with a source of 90 supply of air under pressure in excess of the boiler pressure so as to unseat the check valve 18. A source of supply of combustible fluid will be supplied to the combustion chamber through a pipe 22 which may lead 95 into the pipe 21 and be provided with a perforated or rose end 23 adapted to deliver at a point above the ignition ball 7.

The ratio of pressure for the combustible fluid and the combustion supporting media 100 may be controlled in any desirable manner, not shown, so as to be constant at all times.

It will be clear from the foregoing, that when the ball is heated by a Bunsen burner or like means, it will ignite the oil which falls thereon and under the action of the combustion supporting air introduced into the chamber, combustion will result so that the hot gases will be forced downwardly through pipe 13 into the boiler in a manner to mingle with 110 the contents and evaporate the same for supply under pressure to an engine. The con-

nection of the boiler with an engine is not shown.

In order to prevent excessive heating of the casing 3, forming the combustion chamber, I preferably surround the same with a jacket 24 which may be secured to the boiler 1 so that a portion of the latter will form one wall of the jacket. The top of the jacket is removable and may be in the form 5 of lid 25 having a packing gland 26 through which the pipe 21 is adapted to extend. An inlet pipe 27 delivers to said jacket 24 and may be connected with a source of supply of water under pressure exceeding the pressure 10 in the boiler 1. A return pipe 28 provides for circulation of the cooling medium and is provided with a valve 29 for control of the flow thereof. In some cases, I may connect the jacket 24 with the boiler 1 by a pipe 30 having a valve 31.

In cases where the return connection 28 is used, the valve 31 will be closed and the valve 29 opened to the desired extent in accordance with the rapidity of circulation desired. If the cooling water is to be directed 25 into the boiler 1, valve 29 will be closed and the valve 31 open to the desired extent in accordance with the rapidity of circulation desired. In cases where the connection 30 is used the cooling water in the jacket 24 will 30 be heated prior to its entrance into the boiler and will therefore function as a preheater. In any event the pressure in the jacket 24 will be sufficient to counteract the excessive 35 internal pressure in the casing 3 so as to avoid complication in making the casing 3 heavy enough to wholly resist internal pressure. Furthermore the water in the jacket 24 may also be controlled so that it will take 40 up the heat from the casing 3 only to the extent desired, which result could not be obtained if the casing 3 were disposed in the boiler 1.

It is one of the objects of the device of my 45 invention to employ crude oil as a combustion fluid and it will be seen from the foregoing that practically all of the heat units will be utilized in steam generation thereby wholly eliminating either loss through a 50 smoke stack and likewise the provision of any smoke stack at all.

Furthermore, the device of my invention eliminates the necessity of tubes in the boiler together with the troublesome operations of 55 cleaning the same and the deterioration which constantly takes place even when the tubes are carefully attended.

The device of my invention will be seen 60 to avoid practically all of the disadvantages of steam generation as carried on at the present time, which disadvantages need not further be enumerated.

While I have herein shown and described 65 one form of apparatus, the method of the invention will be clear from the description of

the apparatus, and I wish it understood that I do not wish to be limited to the disclosure made except for such limitations as the claims may import.

I claim:—

1. In an apparatus for generating motive fluid, a generator, a spherical combustion chamber disposed exteriorly of said generator, an inlet for supplies of a combustible fluid and of combustion supporting media 70 under pressure, a diametrically opposed outlet therefor, and a spherical ignition device mounted within said chamber and in symmetrical relation thereto to block a continuous path through said chamber from said inlet to said outlet.

2. In an apparatus for generating motive fluid, a generator, a spherical combustion chamber disposed exteriorly of said generator, a pipe for conducting the products 75 of combustion into said generator from said chamber, an inlet to supply said chamber with a combustible fluid and with combustion supporting media under pressure, a diametrically opposed outlet connecting with 80 said pipe, and a spherical ignition device 85 mounted within said chamber to block a continuous path therethrough from inlet to outlet and to furnish also a continuous ignition of said fluid.

3. In an apparatus for generating motive fluid, a generator, a spherical combustion chamber disposed exteriorly of said generator, a pipe conducting the products 90 of combustion into said generator from said chamber, an inlet to supply said chamber with a combustible fluid and with combustion supporting media under pressure, a diametrically opposed outlet for said chamber to connect with said pipe, and a spherical 95 ignition device symmetrically disposed in said chamber, between said inlet and outlet and of a size sufficiently large to block a continuous path through said chamber and to furnish also a continuous ignition of said 100 fluid.

4. In an apparatus for generating motive fluid, a generator, a pipe leading thereto, a combustion chamber having a larger diameter than said pipe and connected thereto 115 by an outlet, an inlet for said chamber diametrically opposed to said outlet to supply said chamber with a combustible fluid and with combustion supporting media under pressure, a hollow ignition device 120 shaped similarly to and opening on the exterior of said chamber and symmetrically positioned therein to block a continuous path therethrough from inlet to outlet and to furnish also a continuous ignition of said 125 fluid, and heating means for the ignition device leading thereto from without the combustion chamber.

5. In an apparatus for generating motive fluid, a generator, a spherical combustion 130

chamber disposed exteriorly of said generator, a pipe conducting the products of combustion into said generator from said chamber, an air inlet pipe connected with said chamber, a combustible fluid inlet pipe extended into said air inlet pipe having a discharge end directed toward said combustion chamber, a spherical ignition device disposed centrally in said chamber, and a 10 cooling chamber positioned around said combustion chamber.

5 6. In an apparatus for generating motive fluid, a generator, a spherical combustion chamber disposed exteriorly of said generator, said combustion chamber having diametrically opposite inlet and outlet openings, a pipe connected with said outlet openings and extended into said generator

to conduct to the latter the products of combustion, a one-way valve positioned in said pipe to prevent the contents of the generator from entering said pipe, an air inlet pipe secured in said inlet opening, a combustible fluid feed pipe extended into said air inlet pipe and directed toward said combustion chamber, a spherical ignition device supported centrally in said combustion chamber, and means surrounding said combustion chamber for cooling the latter.

15 20 In testimony whereof I affix my signature 25 in presence of two witnesses.

CHARLES E. REORDAN.
